COMBINED SCOURING PAD AND HOLDER

Mark J. Perkovich, Chicago, Ill., assignor to General Foods Corporation, White Plains, N.Y., a corporation of Delaware

Filed Aug. 11, 1958, Ser. No. 52,169

Term of patent 14 years

(Cl. D9—2)

I claim:

The ornamental design for a combined scouring pad and holder, as shown.
